UNITED STATES PATENT OFFICE

113,824

DESIGN FOR A NEGLIGEE

Ethel Eaton Stricker, New York, N. Y.

Application February 8, 1939, Serial No. 82,858

Term of patent 3½ years

To all whom it may concern:

Be it known that I, Ethel Eaton Stricker, a citizen of the United States, residing in New York city, in the county of New York and State of New York, have invented a new, original, and ornamental Design for a Neglige, of which the following is a specification, reference being had to the accompanying drawing, forming part thereof.

Fig. 1 is a front view of a neglige showing my new design;

Fig. 2 is a rear view thereof, and

Fig. 3 is a side view thereof as shown in Figs. 1 and 2.

I claim:

The ornamental design for a neglige, substantially as shown.

ETHEL EATON STRICKER.
